United States Patent

Des. 240,261
Patented June 8, 1976

240,261

LIGHTING FIXTURE

Robert E. Walker, Bellevue, and G. Thomas Henderson,
Bainbridge Island, Wash., assignors to Cascade Pacific
Lumber Co., Inc.

Filed Dec. 5, 1974, Ser. No. 529,806

Term of patent 14 years

Int. Cl. D26—03

U.S. Cl. D48—31

FIG. 1

FIG. 2

FIG. 3

FIG. 1 is a perspective view of a lighting fixture incorporating our new design;

FIG. 2 is a top plan view thereof; and

FIG. 3 is a front elevation view thereof.

The sides of the article which are not shown are substantially identical to the side disclosed in FIG. 3. The bottom of the device is plain and unornamented.

We claim:

The ornamental design for a lighting fixture, substantially as shown and described.
